FUEL PUMP

Carl F. High, Flint, Mich.

Application April 22, 1937, Serial No. 138,389

14 Claims. (Cl. 123—139)

The invention relates generally to fuel pumps for internal combustion engines and more particularly to the control means associated with such pumps for governing the ultimate fuel-air ratio of the mixture supplied to the engine.

When a fuel pump is employed to feed small, accurately measured charges of fuel for the individual cylinders of an internal combustion engine, the relative proportioning of the fuel and

air supply becomes an important consideration in obtaining efficient engine performance at all speeds, and it is customary, therefore, to provide a common interrelated control means for varying the fuel charge and air supply in an

efficient relation throughout the range of engine speeds. In attaining an efficient fuel-air ratio, such a common interrelated control means establishes a definite relationship between the actuation or movement of the fuel volume control and the air volume control throughout the range of engine speeds, and it is found that variations in air pressure incident to altitude changes of an aircraft engine result in a detrimental fuel-air unbalance.

An important object, therefore, of the present invention is to provide a fuel pump for internal combustion engines embodying a new and improved control means whereby an efficiently proportioned air and fuel supply may be provided

at any atmospheric pressure and hence at any altitude of engine operation.

Another object is to provide such a device wherein coordinated mechanism of a simple character for varying the fuel and air supply to

the engine may be adjusted manually to provide, for any particular pressure due to a change of altitude, an efficient fuel-air ratio throughout the range of engine speed.

Another object is to provide a fuel pump having a mixture control means adapted to mounting and operation in aircraft in accordance with principles familiar to most pilots.

More specifically, the present invention has for its object the provision of new and improved fuel and air control mechanism of this character embodying means whereby the pilot may, during flight, adjust the mechanism to deliver, throughout the range of engine speeds, a properly coordinated supply of fuel and air.

A further object is to provide a fuel pump and fuel and air intake control for an internal combustion engine which is automatically variable to change the ratio of fuel to air in accordance with a variation in atmospheric pressure.

Another object is to provide a fuel and air

intake control for an internal combustion engine which is shiftable to change the ratio of fuel to air by the agency of an automatic pressure adjustment operable alternatively with a manual adjustment.

Still another object is the provision of a fuel metering device for an internal combustion engine which is adjustable during regular throttling of the engine to supply different quantities of fuel to satisfy engine requirements under different atmospheric conditions, the adjustments being accomplished selectively by the operator either by direct manual adjustment from the pilot seat or by interposing an automatic adjusting device responsive itself to changes in atmospheric conditions.

A further object of the present invention is the provision of a new and improved fuel and air control mechanism embodying means for throttling the fuel injection during flight to correspond with the air injection in a predetermined ratio and also to provide additional means sealed within a housing for the device, the function of which is to change the predetermined ratio between the fuel and air injection during flight.

A still further object is the provision of a combined fuel and air control mechanism for a combustion engine in which the regular throttle adjustment of the fuel control is connected to the air control so that fuel and air will be simultaneously throttled in a predetermined ratio, and which has in addition a mechanism for altering the ratio between the fuel and air controls capable of being operated during flight independently of the combined fuel and air control means.

Other objects and advantages will become apparent when considered in view of the following description taken in connection with the accompanying drawings, in which:

Fig. 1 is a longitudinal section of one form of fuel pump and control embodying the features of the invention.

Fig. 9 is a somewhat diagrammatic view of a 15 development of a manually operated cam segment showing the relative form of the cam slot.

While there is illustrated in the drawings and shall hereinafter be described in detail a preferred form of the invention, it is to be understood that the invention is not limited to the particular construction and arrangement shown, it 20 being contemplated that various changes may be made by those skilled in the art without departing from the spirit and scope of the invention as expressed in the appended claims.

In the form chosen for the disclosure herein presented, the invention is intended and adapted for use with the internal combustion engines of aircraft machines and is embodied in a fuel and air supply system wherein when the fuel supply 25 to the engine is varied the air supply is correspondingly varied, in order to maintain a constant predetermined ratio between the two under the control of a common accelerator. There is further provided an independent adjustment by 30 means of which the ratio between the fuel and air can be varied in order to satisfy the demand made necessary by operation of the aircraft engine under varied atmospheric conditions at different altitudes or under different barometric pressures. In the embodiment illustrated by the 35 drawings, substantially the entire device is shown, enclosed within a single casing 10 which supports various parts of the device. The casing is in three sections fastened together by appropriate means. Within the upper casing section 11 a cam plate 12 is properly journaled. The mid-section 13 contains a plurality of piston and cylinder devices whose function it is to eject selected 40 quantities of fuel to the corresponding engine cylinders. A lower section 14 forms a sealed compartment 15 within the casing in which are supported various parts of the throttling and adjusting mechanism. A portion of the air intake manifold 16 is shown in Fig. 4 connected for simultaneous operation with parts of the device 45 supported in the lower section 14 of the casing.

It is desired to transmit to the engine liquid fuel and air through separate passages, but so to regulate the respective quantities of fuel and air 50 that the proper proportion is maintained between them so that a more nearly perfect combustion will take place within the engine. With this in mind, it will be apparent that in view of the fact that the proportion of liquid fuel supplied to the 55 engine is considerably smaller in volume than the quantity of air supplied, means will have to be included in the device to reduce the motion of a common throttling mechanism so that only a very small portion of the motion will be used in 60 adjusting the quantity of liquid fuel while a correspondingly larger portion of the motion will be used to regulate the quantity of air.

It will be further evident, particularly when 65 the combustion engine to be supplied with fuel 70 is used in an aircraft, that due to changes in

altitude or barometric changes the same volume of air will not be drawn in with a given throttle valve setting or that the same volume of air will not necessarily contain the same quantity of oxygen needed for combustion. To compensate 5 for such a variation it will be necessary from time to time to change the fuel-air ratio. Since such a change should be independent of the common throttling mechanism, an independent adjusting mechanism is supplied by means of which 10 a pilot may, by the manipulation of a suitable control, change the setting of the valve which admits fuel so that in response to the common throttling mechanism a different quantity of liquid fuel will be admitted as compared to the usual 15 quantity of air. In the embodiment shown, the mechanisms controlling both the throttling and the adjusting functions are all substantially housed within the same casing.

Although it is desirable to have the adjustment of the fuel-air ratio under the control of the pilot, occasions arise when it is convenient to have the change made automatically and for the preferred form of fuel control disclosed herein there is shown and described both a direct 20 manual adjustment and a manual adjustment combined and alternatively operable with an automatic adjustment responsive to changes in atmospheric conditions, either of which may be used with the same common throttling mechanism. 25

So that the operation may be more easily understood, the description is devoted first solely to the application of a direct manually operated adjusting means for changing the fuel-air ratio. 30 Having had the general principle thus presented, the construction of a device featuring an automatic adjustment together with a selective manual adjustment to be subsequently described, will be readily understood. 40

In Fig. 4, fuel is introduced to the device at an inlet 20 in the lower section 13 of the casing 10 where it fills a chamber 24 together with the lower sealed compartment 15. Either gravity or pump pressure may be utilized to drive the fuel 45 into the device. Excess fuel not passed to the engine finds its way from the chamber 24 out through the port 25 from which it passes upward through a passage (not shown) within an enlargement 23 on the casing (Fig. 4) from 50 which it is led to a fuel passage 21 at the upper section 11 of the casing 10. A plugged hole 21' is shown which may be opened and have attached thereto a return line to conduct fuel back to the supply tank. From the sealed compartment 15 fuel is conducted past a fuel metering valve device indicated generally by the numeral 55 26 and passes through appropriate passages 27 in the casing and is discharged periodically, by suitable pistons to be subsequently described, 60 from the outlet ports 28, 29, 30, etc., depending upon the timing of the engine. Each outlet port supplies a separate cylinder of the combustion engine and the frequency of the discharge is correspondingly timed to suit the engine operation. 65

Since it is desired to vary the quantity of liquid fuel admitted in order to suit different operating conditions, the position of the metering valve device 26 is designed to be changed in response to various manual or automatic adjusting mechanisms. The valve device itself consists of primarily a tapered metering pin 31 attached to a downwardly extending cylindrical portion 32 which has a recess 33 at the bottom in which is supported a bearing member 34 in the form 70 75

of a ball. An internal section on arm 35 is shown which is one of a number of elements of a spider within the chamber 24, all of which are joined in a central portion 36. The central portion has inserted at the lower side a plug element 37 forming a seat 38 for the metering pin and also a supporting sleeve 39 for the cylindrical portion 32. Liquid fuel from the chamber 24 and from the compartment 15 joined thereto may be passed through passages 40 in the plug 37 and thence upward past the metering pin to the passages 27. A coiled spring 41 is shown surrounding the lower part of the plug 37 which tends to yieldingly extend the cylindrical portion 32 and the metering pin 31 outward with respect to the seat 38, thus tending to open a passageway for the passage of liquid fuel.

The liquid fuel having been permitted to pass the metering pin must be ejected at proper intervals through the outlet ports 28, 29, 30, etc. To accomplish this, a combined reciprocating and rotating piston 42 is employed. The piston reciprocates in and out of a cylindrical chamber 43 subject to impulses given it by the cam plate 12. By an appropriate means the cylinder is likewise rotated a small fraction of a turn and this rotation, together with the appropriate reciprocation periodically raises a port 44 in the piston presenting it at such periods to its corresponding passage 27, admitting a quantity of fuel depending upon the amount admitted by the position of the metering pin. After a quantity of liquid fuel has been admitted to the piston, it is reciprocated downwardly closing the port 44 and, by this downward motion liquid entrapped thereby within a pocket 45 and the chamber 43 is forced outward to its corresponding outlet passage when the piston is rotated to present the port 44 to the passage.

The piston 42 has a head at the top in which is formed a socket 46 and around which protrudes an annular shoulder 47. Within the mid-section 13 of the casing is a bushing 48 adjacent each cylinder which supplies a support for a helical spring 49. There is likewise a chamber 50 formed within the mid-section 13 in which the top portions of the pistons reciprocate flooded with a bath of oil. The topmost portion of the cylinder 42 extends through an aperture 51 in a partition 52 located between the upper section 11 and middle section 13, the edges of the aperture 51 forming a stop for limiting the upward motion of the cylinder by reason of being urged upward by the spring 49.

A ball and socket joint is formed by the socket 46 together with a bearing member 53 which has a cam shoe 54 at the top. It will be noted that a lower face 55 of the cam plate 12 slopes from one side to the other so that as the cam plate rotates the cylinder 42 will be alternately pressed downward through the ball and socket joint through an expelling stroke, and upward through a loading stroke, the latter stroke being accomplished through the agency of the spring 49.

A cam groove 56 is formed in the bottom face 55 of the cam plate 12 and has a particular shape in order properly to oscillate the pistons. A cam follower 57 associated with each piston extends into the cam groove so that each time the piston is driven through a reciprocating stroke it is likewise given a partial rotation for the purpose previously described, that of rotating a port in the cylinder to a proper position for expelling liquid fuel. A more detailed description of this portion of the structure is given in

my Patent No. 2,060,076, issued November 10, 1936. The cam plate 12 has an axial hollow shaft 58 formed integrally with it, the hollow shaft being journaled in a bearing hub 59 located above the upper section 11 of the casing 10 by means of a friction bearing 60. Above the bearing hub 59 is a fixed flange 61 located on a drive shaft 63 for holding the parts in place at the upper end. The lower end of the drive shaft 63 is secured to the cam plate by means of a one-way clutch 62 described in detail in my application Serial No. 124,063, filed February 4, 1937, and the cam plate is secured longitudinally to the cam shaft 63 by means of a castellated nut 65 and cotter pin 66. In order to take up thrust upon the rotating mechanism just described, a radial thrust bearing 64 is supplied, held in position in the casing by a screw 64', for rotatably guiding the axial hollow shaft 58 in the upper section of the casing. Lubricating oil may be introduced at an inlet 67 near the top, from which it may pass through a system of conduits 67' within the device to supply lubricating fluid to the moving parts. A return outlet 81 is shown in Fig. 4 for the lubricating oil.

The metering pin is caused to move upward and inward against its seat by means of rotation of a fuel cam 70 and the cam is in turn rotated through a system of levers from the pilot's seat. It will be noted (Fig. 3a) that the contacting surface 71 of the cam is shaped so that a different displacement will be given to the metering pin depending on the degree of rotation. It should be further noted that the surface 71 is a warped surface in which one end follows the contour of the cam, the other traversing a wavy line which approaches and recedes variously from the center of rotation. The purpose of the warped surface will be subsequently disclosed.

As best seen in Fig. 3, the fuel cam 70 is non-rotatably supported upon a horizontal cam shaft 72 which rides in and out of a horizontal sleeve shaft 73. The horizontal cam shaft 72 is urged outwardly by a coiled spring 74 located in the inner hollow space 75 within the sleeve shaft. A threaded plug 74' holds the spring in place and closes the space 75. At the end of the horizontal shaft 72, opposite from the spring, a shoulder 76 is formed which bears against the inner side of the cam 70 and tends to push it outward. The cam is secured to the shaft by a nut 77 and the entire assembly is urged inward against the force of the coiled spring by means of a first class lever 78 and an auxiliary adjusting mechanism indicated generally as 79.

The horizontal shaft 72 has a squared portion 72' for holding it non-rotatably in a squared hole in the sleeve shaft 73 which at the same time permits the horizontal shaft to shift horizontally so that the plane of rotation of the cam can be moved to the right or left, meanwhile, the relative position depends directly on the rotating movement given to the sleeve shaft. Non-rotatably attached to the outer or right-hand end of the sleeve shaft 73 is a rocker arm 82 which is held in this position by a pair of lock nuts 83 and 84, the outer nut 84 being additionally locked in position by means of a pin 85. Attached to the free end of the rocker arm 82 is a rod 86 which has an adjusting swivel 87 at the approximate center for changing its relative length. The other end of the rod 86 is swivelled to a rocker arm 88 which is attached to a butterfly valve 89 located in the air intake manifold 16. By this means the action of the metering valve corre-

sponds with the action of the air intake valve. Both valves are jointly operated by a common throttle connection 89' which is operated from the pilot's seat.

It has been found desirable to have a substantial portion of the rocking parts of this cam mechanism located within the casing 10 and to accomplish this the cam mechanism parts referred to are located and supported by the lower section 13 of the casing and will be observed to be located in the compartment 15 which is always flooded with liquid fuel. Consequently the mounting of the horizontal shaft 72 which supports the cam must be sealed to prevent any leak of liquid fuel at this point. A multiple packing joint is therefore supplied consisting of an inner bushing 91 and an outer bushing 92, the central portions of both being located in a chamber 93 at the left side of the lower section 13 of the casing. The parts 91 and 92 are threadable one into the other so that they will be securely tightened against gaskets 94 and 95 to make a fluid-tight joint with the lower section 13 of the casing. Located within the bushings 91 and 92 is a central axial passage for supporting the rotating sleeve shaft 73 which must rotate in order to properly move the cam during operation. An additional packing 98 effectively seals this passage and is spring pressed into place by means of a coiled spring 99 bearing against a packing ring 100 to press the packing 98 into contact with the sleeve shaft.

The device is provided with an idling adjustment consisting essentially of a screw 96 fixed at its inner end in the part 91 and extending loosely through the lower casing section 14 and a rotatable adjusting nut 97 provided with spanner wrench holes. The nut 97 is rotatable but is held against axial movement by pins 97' extending through the hub on section 14 and into an annular groove 97" formed in the nut 97. When it is desired to change or adjust the idling position, the fuel cam 10 is rotated to idling position, the parts 91 and 92 are loosened slightly and the nut 97 turned so as to move the whole mechanism bodily upward or downward a slight amount in order to change the setting of the metering pin at the idling position. When this has been satisfactorily adjusted, the parts 91 and 92 are again locked in adjusted position.

As viewed in Fig. 1, when it is desired to increase the flow of liquid fuel past the metering pin, the fuel cam 10 is rotated in a clockwise direction. This rotation is accomplished by means of rocker arm 82, the rod 86 and the throttle connection 89' previously described. As the cam is rotated clockwise the cylindrical portion 39 is urged downward by the spring 41, thus permitting the metering pin to be withdrawn, enlarging the passage at the seat 38 for the passage of liquid fuel. At full open position a flat face 101 on the cam abuts one side of a stationary shoulder piece 102 and at idling position a pin 103 abuts the other side of the stationary shoulder piece 102. In the idling position a flat resilient land is provided for the metering pin, which consists of a piston 104 slidably secured by a loose fitting pin 105 in a recess near the outer face of the cam, as viewed in Fig. 3. The piston 104 is urged upward against the ball 34 in the cylindrical portion of the metering pin by means of a coiled spring 106 which bears at its bottom end against the horizontal cam shaft 72.

While the cam is held in one position so that

it rotates always in the same plane, there will be maintained a constant ratio between the quantity of liquid fuel admitted to the engine and the quantity of air admitted through the air intake manifold for all of the various rotative cam positions, since when the cam is rotated to change the setting of the metering pin, the opening of the air intake valve is likewise changed. On occasions when it is desired to change the fuel-air ratio, parts best seen in Figs. 1* and 3* are manipulated. Such a change can be accomplished by shifting 10 the plane of rotation of the cam so that the ball 34 in the cylindrical portion of the metering pin is extended further outward in a downward direction as the warped face 71 of the fuel cam is extended, as viewed in Fig. 3, outward or to the left. 15 A shift of the shaft 72 carrying the fuel cam toward the left as indicated makes it necessary that metering pin open a greater amount as the spring 41 forces the ball 34 against a different portion of the sloping warped face 71 of the fuel cam, 20 although the latter is rotated only the same amount as it may previously have been rotated for a desired engine speed.

During flight it is frequently desired to change the fuel-air ratio from the pilot seat. To make 25 such an adjustment effective upon the device a suitable manual adjusting means is provided. This means consists of the first class lever device previously referred to as 78, which is pivotally secured to the lower section 14 of the casing by 30 means of a screw 107 and a lock nut 107'. One end 110 of the lever 78 pushes directly against the horizontal shaft 72 and the other end 111 is provided with a roller 112 adapted to ride on an annular adjusting cam face 113 formed on a head 35 114' of a shaft 114. The head 114' is provided with a pin 108 which abuts stationary stop pins 109 on the casing. This last mentioned shaft is rotated by means of a rocker arm 115 non-rotatably attached to the shaft by means of 40 the lock nuts 116 and 117 which are keyed to the shaft. The rocker arm 115 has a direct independent connection 118 to an adjustment on the instrument board in the cockpit. It will thus be observed that by rotation of the 45 shaft 114' the cam face 113 will be shifted so as to change the position of the first class lever 78. When the shaft is rotated in a direction so as to permit the end 110 of the first class lever to move outward, as viewed in Fig. 3, which corresponds to an upward movement, as viewed in Fig. 2, the fuel cam 10 will be urged in a corresponding direction by means of the coiled spring 74 which movement will shift the plane of rotation of the cam. The adjustment described will 50 permit the cylindrical portion 32 of the metering pin to more nearly approach the center axis of the fuel cam 10 as the cam is rotated in this newly adjusted position, so that a different opening of the metering pin being provided to establish 55 a new fuel-air ratio for the engine when the cam is subjected to different regular adjustments of the common throttle throughout the range of engine speeds.

Because the parts associated with the first class 65 lever 78 are located in the compartment 15 within the casing, it is desirable also to seal the shaft 114 in order to prevent fluid leaks. To that end there is supplied a packing nut 118 and a packing sleeve 119 which secure a packing ring 120 by 70 means of a coiled spring 121 bearing against a packing washer 122.

It will be evident then that the rocker arm 82 controlling the fuel cam 10, together with the air control rocker arm 88, have a range of relative 75

throttling positions, whereby to control the engine speed by supplying a fuel and air mixture at a constant ratio but in different quantities. Furthermore the ratio or proportion of fuel to air may by a suitable mechanism be varied at will, while the engine is in operation, in order to adjust or tune it to respond more efficiently to different pressure conditions in the atmosphere.

There are times during flight, however, when it

10 is advantageous for a pilot not to be compelled manually to make constant changes in the fuel-air ratio and for this reason an automatic pressure adjustment coupled alternatively to the manual adjustment is of singular utility.

15 To provide an automatic adjustment together with an manual adjustment, a mechanism of the type illustrated in Figs. 5 through 9 is incorporated in the invention. This mechanism is supported in a lower casing or section 14' attached to 20 the mid-section 13 of the casing 10 in the same general manner as has been previously described for the mechanism supported in the lower section 14 shown in Figs. 1 through 4. The throttle control occupies the same relative position as does 25 also the manually operated portion of the adjusting means, the difference being primarily in the addition of an automatic adjusting portion located axially with respect to the horizontal fuel cam shaft 72.

30 A fuel cam 70' is designed in a form slightly different from the fuel cam 70 originally referred to in order to provide for a combination of connections, one for the manually operated portion of the adjusting means and another for the automatic portion. The cam has a warped surface of 35 the same type as has been previously described and is fixed non-rotatably to the shaft 72 which is shiftable from left to right and vice versa. It will be noted, however, in this modification that 40 the inner hollow space 75 is empty since no spring is necessary to shift the shaft toward the left. The shifting in both directions is accomplished directly by the manipulation of either the manual or the automatic adjusting means.

45 Although the principle of operation of the manually operated portion of the adjusting means is the same in this modification as in the form illustrated in Figs. 1 through 4, some changes in design are requisite in order to have the manually 50 operated portion of the adjusting means cooperable with the automatically operated portion thereof. With this in view, there is provided a two-piece arcuate cam segment 130, parted substantially at the middle to form two opposed 55 halves, forming a portion of what may be termed a manual mixture control cam which is non-rotatably fixed to a shaft 131 suitably journaled in a lower section 14' of the casing 10. The shaft is rotated in the usual manner by means of a 60 mixture control rocker arm 115' locked to the shaft by the nuts 116' and 117'. Here also a packing nut 118' cooperating with a packing sleeve 119', a packing ring 120' and a coil spring 121' serve to hold a packing washer 122' in its 65 recess in order to rotatably seal the shaft 131 in place. It will thus be apparent that by rotating the rocker arm 115' the mixture control cam can be rotated to a desired position.

Motion induced by the mixture control cam is 70 transferred to the fuel cam 70' which operates on the metering valve, by means of what may be termed a mixture control yoke consisting of a first class lever 135. The lever is fulcrumed more or less at its mid-point to a block or base 136 by 75 means of a rivet 137 so that the lever is free to

swing when urged in either direction by the mixture control cam. The device is unique in that the block or base 136 is pivoted by means of projections 138 journaled in the opposite halves of the cam segment 130 in concentric alinement with the shaft 131 attached thereto, as will be most apparent in Fig. 8. The halves of the cam segment 130 are held together by means of screws 139.

80 At one end the first class lever 135 is provided with a roller 140 which rotates freely upon the lever and travels over the surfaces at either side of a cam slot 141 formed between the halves of the cam segment 130. Since the cam slot 141 is disposed in a position at an angle to the plane of rotation of the cam segment 130, the roller will be moved back and forth as the segment is rotated. At its other end the lever is bifurcated as at 142 and loosely engages a portion of the fuel cam 70'. It will be noted that the cam 70' has an annular recess 143 in which the bifurcated portions of the lever are permitted to ride and since there is an annular shoulder 144 at the right side and a similar annular shoulder 145 on the left side, as viewed in Fig. 6, the motion 85 caused by tilting the lever 135 in either direction will be transferred directly to the cam 70' causing it to change the plane of its rotation accordingly. It will be apparent then that the fuel-air ratio of the metering device can be altered manually at the will of the operator 90 independently of the throttling means. While the shaft 131 is being rotated the fulcrum of the lever 135 will pivot with respect to it and the lever will be held in position, subject to being 95 tilted in one direction or the other depending on which side of the cam slot 141 is pushing against the roller 140.

The automatic means previously referred to 100 is operative alternatively with the manual adjusting means just described in such a way that either one or the other is always controlling the ratio of the fuel-air mixture. In the form illustrated in Figs. 5 and 6, the automatic means is shown to consist of a pressure responsive bellows forming a resiliently extensible member so mounted that it will expand or contract with changes in atmospheric pressure and transmit its adjustment directly to the fuel cam. A threaded extension 150 is provided on the left 105 hand side of the lower portion 14' of the casing and to it a cup-like member 151 forming a receptacle is attached by means of a sleeve member 152. In the member 152 are spanner wrench holes 152' used for securing the member 151 in place and for adjusting it once in place. Within the receptacle is a resiliently extensible bellows 153 mounted at its base upon the sleeve member 152 at a point 154 where it is sealed 110 tightly in order to make an air-tight pocket 155 within the receptacle. A cap 156 closes the upper or left hand end of the bellows.

In order to attach the bellows to the cam 70' there is provided a connecting pin 157 secured 115 at one end by means of a pin 158 to the cap 156 and swivelly attached at the other end to the fuel cam 70' by means of a button and claw fitting 159. In order properly to mount the pin 157 the extension 150 is provided with a sleeve-like portion 161 and has a hollow space 162 in which are positioned elements of a packing gland consisting of a packing 163, a packing ring 164, a coiled spring 165 and a retaining nut 166, which is effective in preventing any fuel ac- 120 75

cumulating in a chamber 15' from filling an air space 167 within the bellows.

In the wall of the receptacle 151 there is positioned a valve 168 over which is screwed a cap 169 and by this means a greater or lesser amount of gas can be forced into the sealed pocket 155. On the opposite side of the bellows a bleed hole 170 is drilled through the sleeve member 152 in order that the space 167 within the bellows may be subjected to atmospheric pressure. It will be understood from this that since the quantity of gas sealed within the pocket 155 remains constant any change in atmospheric pressure on the opposite side of the bellows will tend to expand the bellows or contract it, causing the cap 156 to move toward the left or right. Such motion induced in the cap will be directly transmitted by means of the pin 157 to the fuel cam 70', producing a corresponding adjustment in the fuel-air ratio.

When it is desired to calibrate the bellows, gas can be introduced through the valve 168 to an amount such that the pressure on the sealed side of the bellows is in proper proportion to atmospheric pressure. A mechanical calibration is also available by resorting to the expedient of screwing the sleeve member 152 on or off the extension 150. The bellows may thus be distended or contracted to produce a greater or lesser tension on the pin 157 and a corresponding reactance to atmospheric pressure.

In order that the automatic pressure adjustment may function freely and not be restricted by the manually operated portion of the adjusting means, the cam slot 141 has been specially constructed, as will be more clearly seen in the development of the cam slot shown diagrammatically in Fig. 9. It will be noted that one of the sloping ends of the cam slot has a uniform width, this being the portion 141' of the slot used when it is desired to adjust the device directly by means of the rocker arm 115'. Since the roller 140 is but slightly smaller in diameter than the space between the faces of this portion of the cam slot, it will be urged in one direction or the other depending upon the direction of rotation of the cam segment. When it is desired to have the automatically adjusted portion operate independently, the cam segment can be rotated so that the roller 140 passes to an enlarged portion 141'' of the slot 141, shown at the left end as viewed in Fig. 9. The left end of the slot is considerably wider than the diameter of the roller 140 and has the effect of permitting it to tilt freely back and forth therein. Therefore, when the pilot wishes, as a matter of convenience, to have the automatic adjusting means operate he has only to rotate the mixture control cam until the enlarged portion 141'' of the slot 141 engages the roller 140, then when the bellows 153 moves the cam 70' to the right or left the lever 135 is free to tilt in one direction or the other without being restricted by the surfaces of the cam slot. When it is again desired to make the adjustments manually, the mixture control cam is rotated back again so that the walls of the end 141' of the cam slot bear directly against the roller 140 and force it in one direction or the other at the will of the operator. There is sufficient resiliency in the automatically operated portion so that no evil effects will result from forcing it the comparatively small distance in one direction or the other necessary to produce manually the desired adjustments of the cam 70'.

There has thus been provided a mechanism for maintaining a predetermined fuel-air mixture to be supplied to a combustion engine having a double alternative adjustment, one part operated automatically and the other part manually by means of which the ratio of fuel to air can be changed to suit different atmospheric conditions while the metering means is in operation. Substantially all of the parts are compactly housed and sealed within a casing supporting the various mechanisms, all of which may be constantly lubricated by the liquid fuel itself.

I claim as my invention:

1. A fuel and air supply system for an internal combustion engine comprising an air intake manifold and a valve having means for actuating the same, a fuel distributing device having a plurality of fuel impelling elements for supplying fuel to the engine, fuel control means for varying the fuel supply to the engine, a shiftable cam element rotatable in contact with said fuel control means, and manually operable throttle means interconnecting the cam element and the actuating means of the air intake valve so that the ratio of fuel to air supply to the engine is maintained at a definite ratio irrespective of the quantity of fuel admitted to the engine throughout the range of engine speeds, and independent adjusting means directly operable upon said shiftable cam element to shift the position thereof with respect to said fuel control means and cause a change in the fuel-air ratio dependent upon the respective movements of the fuel control means and the air intake valve.

2. A fuel and air supply system for an internal combustion engine comprising, in combination, an air intake manifold, air control means therein, a fuel source for supplying measured quantities of fuel to the engine, fuel control means for varying the quantity of fuel supplied by said fuel source including an adjustable member, an axially shiftable rotating means of varying diameter contacting the adjustable member for changing the position of said member, manually operable throttle means interconnecting said rotating means and said air control means so that the quantity of air passing said air control means is changed in accordance with a definite ratio to correspond with the quantity of fuel admitted by the fuel control means throughout the range of engine speeds, means for adjusting the rotating means axially to effect a change in the ratio of movement between the adjustable member and the air control means, and manual control means for said last mentioned means having an operation independent of the throttle means.

3. A fuel and air supply system for an internal combustion engine comprising, in combination, an air intake manifold, an air intake control means therefor, an adjustable fuel supply means, fuel control means for varying the quantity of fuel supplied by said supply means, rotatable and axially shiftable cam means for adjusting said fuel control means, said cam means having a warped surface, manually operable throttle means interconnecting said cam means and said air control means so that the ratio of the quantity of fuel to the quantity of air is maintained at a definite value throughout the range of engine speeds for a given axial position of said cam means, means for adjusting the cam means axially independently of the throttle means in order to render effective a different portion of the warped surface of said cam means to cause a change in the fuel-air ratio, and manual control means at-

tached to said adjusting means for effecting an independent adjustment thereof.

4. A fuel and air supply system for an internal combustion engine comprising, in combination, an air intake manifold, an air intake control means for the manifold, an adjustable fuel supply means, an axially shiftable and rotatable cam element having a warped circumferential surface cooperating with a part of the fuel supply means and operable upon rotation to change the adjustment of the fuel supply means, throttling means for imparting desired rotation to said cam element and for actuating said air intake control means, an adjusting mechanism for altering the effect of cam rotation upon the adjustable fuel supply means comprising a lever and a cam in contact therewith for shifting said cam element axially to render a different portion of the warped surface of said cam element effective for controlling said adjustable fuel supply, and control means for imparting desired movement to said second mentioned cam.

5. A fuel and air supply system for an internal combustion engine comprising an air intake manifold, a control valve therefor having means for actuating the same, a fuel pumping device for supplying fuel to the engine, fuel control means for varying the quantity of fuel supplied to the engine including a control element, a shiftable cam means having a warped surface for contact with said control element for changing the position thereof, manually operable throttle means interconnecting the cam means and the actuating means for the air control valve so that the ratio of the quantity of fuel to the quantity of air supplied to the engine is maintained at a definite amount throughout the range of engine speeds, and independent adjusting means directly operable upon the shiftable cam means to shift the cam means axially in order to present a different portion of the warped surface of the cam means to the control element and cause a change in the fuel-air ratio.

6. A fuel and air supply system for an internal combustion engine comprising, in combination, an air intake manifold and a valve therein having means for actuating the same, variable fuel supply means having a control element for determining the quantity of fuel supplied thereby to the engine, a shiftable cam means pressing against said element for changing the position of said element to vary the adjustment of said fuel supply means, said cam means having a warped surface with which said control element cooperates, manually operable throttle means interconnecting the cam means and the actuating means for the air intake valve so that the ratio of the quantity of fuel to the quantity of air is maintained at a definite amount throughout the range of engine speeds, and adjusting means directly operable upon the shiftable cam means to shift the position thereof relatively to the air valve in order to change the fuel-air ratio.

7. In a fuel and air supply system for an internal combustion engine, air control means, fuel control means, and actuating mechanism for the air and the fuel control means comprising a rotatably mounted sleeve, manually operable linkage interconnecting said sleeve and said air control means simultaneously to rotate said sleeve and to actuate said air control means, a cam element having a warped circumferential surface the radii of the surface varying both when considered in an angular direction and also in a direction axially of said cam, said cam being

mounted in said sleeve for rotation therewith and for movement longitudinally thereof and the cam surface cooperating with the fuel control means to vary the quantity of fuel supplied thereby as the cam is rotated, and means for shifting said cam axially relative to said fuel control means and said sleeve to render a different portion of the cam effective to govern the fuel control means, thereby to vary the ratio of fuel and air supplied to the engine.

8. In a fuel and air supply system for an internal combustion engine, air control means, fuel control means, and actuating mechanism for the air and fuel control means comprising a rotatably mounted element, manually operable linkage interconnecting said element and said air control means simultaneously to rotate said element and to actuate said air control means in a predetermined relationship, a member mounted in said element for rotation therewith and for movement longitudinally thereof, said member being operatively associated with the fuel control means to vary the quantity of fuel supplied thereby to the engine, said member upon rotation while in one axial position relative to said element varying said fuel control means to maintain a predetermined fuel-air ratio throughout the movement of the manually operable linkage and upon rotation while in a different axial position relative to said element maintaining a different fuel-air ratio, and means for shifting said member axially relative to said element.

9. A fuel discharge mechanism for supplying fuel to a combustion engine comprising a pump device connected to the engine, a fuel control element, throttling means operatively associated with said element and operable to move the element so as to vary the fuel supplied to the engine, automatic adjusting means for said throttling means comprising means responsive to atmospheric pressure having an operative connection with the throttling means for varying the setting of the throttling means in accordance with pressure variations, and a manual adjusting means for said throttling means comprising a cam and lever means connected with the throttling means for shifting the setting of said means at will, said cam and lever means being provided with a loose connection in one position of adjustment to allow shifting of the throttling means by the pressure responsive means unrestricted by action of the manual adjusting means.

10. A fuel discharge mechanism for supplying fuel to an internal combustion engine comprising a pump device connected to the engine, a fuel control element, throttling means operatively associated with said element and operable to move the element so as to vary the fuel supplied to the engine, pressure responsive adjusting means having an operative connection with the throttling means for varying the setting of the throttling means with changes in atmospheric pressure, and a manual adjusting means comprising a rotatable cam segment having a cam slot therein with an enlarged portion, a pivoted lever means having at one end a cam follower movable in the slot in said cam segment and having its other end engaged with the throttling means for variably shifting the setting of said means alternatively with said pressure responsive means, said cam segment being rotatable to position said cam follower in the enlarged portion of said slot to allow shifting of the throttling means by the pressure responsive means un-

- restricted by action of the manual adjusting means.
11. In a fuel and air supply system for an internal combustion engine, in combination, a fuel control means, a shiftable element for adjusting said control means, an automatically operable pressure responsive means for shifting said element, and a manually actuatable means operable to take over the shifting of said element
- 10 comprising a rotatably mounted cam segment having a cam slot therein enlarged at one end, lever means fulcrumed on a block pivotally mounted in the cam segment and having at one end a cam follower received in the slot and having its other end engaged with the control means for variably shifting the setting of said means alternatively with the shifting occasioned by said pressure responsive adjusting means, said cam segment being movable manually to govern
- 15 the shifting of said element or to a position with respect to the cam follower allowing shifting of the control means by the pressure responsive means unrestricted by the manually actuatable means.
12. In a mechanism for supplying fuel and air to an internal combustion engine, in combination, a valve controlled air intake, a variable fuel supply, a control element for varying the quantity of fuel supplied by the fuel supply, throttling
- 20 means connected with the valve in said air intake and operatively associated with said control element so as to vary the control element and the valve simultaneously and in corresponding amounts, and a manual adjusting means comprising a cam segment having a cam way therein and a lever pivotally mounted in the cam segment and having at one end a cam follower movable by the cam way and having another end engaged with the throttling means for variably
- 25 shifting the setting of said means to provide for varying the control element by different corresponding amounts when said throttling means is moved throughout said range of relative positions.
13. In a fuel supply system for an internal combustion engine, in combination, a fuel control means and governing mechanism for the fuel control means comprising a throttling means

associated with said fuel control means to vary the quantity of fuel supplied to the engine, an automatically operable pressure responsive means connected with said throttling means to shift the same in accordance with pressure variations, and manually actuatable means operable to wrest shifting control of said throttling means from said pressure responsive device and vest shifting control in the manually actuatable means or to permit unrestrained shift of said throttling means by said pressure responsive means.

14. In a fuel supply system for an internal combustion engine, a fuel control means and governing mechanism for said fuel control means comprising a rotatable member having means for actuating the same manually, an element mounted in said member for rotation therewith and for axial adjustment relative thereto, said element being operatively associated with said fuel control means to vary the quantity of fuel supplied to the engine as the element is rotated, said element being constructed to modify the effect of its rotation upon the fuel control means depending upon the axial position of said element relative to said member, pressure responsive means connected with said element for shifting the same axially in accordance with pressure variations, and manually actuatable means operable to permit unrestricted shifting of said element under the control of said pressure responsive means or to wrest shifting of said element from said pressure responsive means, said manually actuatable means comprising a rotatably mounted segment having a cam slot therein, a lever pivotally mounted intermediate its ends and at one end carrying a cam follower engaging the cam slot and at the other end engaging said element, said cam slot through a portion of its length confining said cam follower to prevent pivoting of the lever relative to the cam slot and throughout the remainder of its length being enlarged to permit movement of said lever whereby the pressure responsive means is placed in control of said element, and manual means for rotating said segment to place the cam follower in a desired portion of said cam slot.

CARL F. HIGH.
